UNITED STATES PATENT OFFICE.

THEODORE ZIOCK, OF ST. LOUIS, MISSOURI.

SCARF.

1,027,580.

Specification of Letters Patent. Patented May 28, 1912.

Application filed July 6, 1909. Serial No. 506,034.

To all whom it may concern:

Be it known that I, THEODORE ZIOCK, a citizen of the United States, residing at St. Louis, Missouri, have invented a certain new and useful Improvement in Scarfs, of which the following is a full, clear, and exact description, such as will enable others skilled in the art to which it appertains to make and use the same, reference being had to the accompanying drawings, forming part of this specification, in which—

Figure 1 is a detailed view of my improved scarf. Fig. 2 is a sectional view on line 2—2, Fig. 1. Fig. 3 is a view illustrating my improved scarf in position.

This invention relates to a new and useful improvement in scarfs, or neckties as they are commonly called, the object being to construct a scarf so that it will slide freely and easily through a turndown or folded collar. Turndown collars as now commonly made and sold are provided with a buttonhole at the back through which the end of the collar button projects and when the scarf is placed in position, if it is above the button, it is caught in the wedge-shaped opening and prevented from sliding, or it is stretched over the head of the button and pressed there-between and the outer fold of the collar so that it cannot move with freedom.

My invention consists in providing the necktie with a slot, so that the head of the button may project through and provide an open sliding space for the tie at the back of the collar.

In the drawings, 1 indicates the scarf which may be of any design or pattern, and preferably made of the same kind of material throughout its length. In the back of the neck portion of the scarf, there is an opening 2, preferably four or five inches long to enable ready adjustment of the tie, said opening being finished by button-hole stitching or any desired form of stitching 3. If desired to reinforce the tie at this point, 45 crinoline or other stiffening or reinforcing material 4 may be employed as shown in Fig. 2.

Having thus described my invention, what I claim is:

A scarf made of the same kind of material throughout its length and provided with a long slot extending longitudinally in the neck encircling portion for receiving a collar button, and stiffening strips secured in 55 said scarf extending from said slot to the edges of the scarf whereby said portions of the scarf are held flat and extended for the purpose of preventing said portions folding 60 upon one another.

In testimony whereof I hereunto affix my signature in the presence of two witnesses, this 1st day of July, 1909.

THEODORE ZIOCK.
